UNITED STATES PATENT OFFICE

144,308

DESIGN FOR A FUSELAGE FOR GROUNDED AVIATION TRAINERS

Karl A. Kail, Montrose, Pa., assignor to Link Aviation Devices, Inc., Binghamton, N. Y., a corporation of New York

Application April 18, 1945, Serial No. 119,072

Term of patent 14 years

(Cl. D71—1)

To all whom it may concern:

Be it known that I, Karl A. Kail, a citizen of the United States, residing at Montrose, in the county of Susquehanna and State of Pennsylvania, have invented a new, original, and ornamental Design for a Fuselage for Grounded Aviation Trainers, of which the following is a specification, reference being had to the accompanying drawings, forming part thereof.

Fig. 1 is a side elevational view of a fuselage for grounded aviation trainers showing my new design.

Fig. 2 is a front elevational view thereof.
Fig. 3 is an elevational view of the side opposite that shown in Fig. 1, and
Fig. 4 is a rear elevational view.
Fig. 5 is a perspective view thereof.
I claim:
The ornamental design for a fuselage for grounded aviation trainers, as shown.

KARL A. KAIL.
